DESIGN FOR A TEXTILE FABRIC

Sidney Breakstone, New York, N. Y.

Application December 17, 1936, Serial No. 66,582

Term of patent 3½ years

To all whom it may concern:

Be it known that I, Sidney Breakstone, a citizen of the United States of America, residing in Manhattan, county of New York, and State of New York, have invented a new, original, and ornamental Design for a Textile Fabric, of which the following is a specification, reference being had to the accompanying drawing, forming part thereof, wherein,

The figure is a plan view of a piece of textile fabric showing my new design.

The design is characterized by groups of parallel blocks formed of light and dark strokes of uneven dimensions, each of the light strokes being repeated by the dark shadow stroke beneath.

I claim:

The ornamental design for a textile fabric, substantially as shown and described.

SIDNEY BREAKSTONE.
